UNITED STATES PATENT OFFICE.

WALTER HUNT REDMAN, OF NEWARK, NEW JERSEY, ASSIGNOR, BY MESNE ASSIGNMENTS, TO H. BOKER & CO., INC. (OF N. J.), OF NEW YORK, N. Y., A CORPORATION OF NEW JERSEY.

HAIR CLIPPER.

Application filed May 2, 1919. Serial No. 294,237.

To all whom it may concern:

Be it known that I, WALTER H. REDMAN, a citizen of the United States, and a resident of Newark, in the county of Essex and State of New Jersey, have invented certain new and useful Improvements in Hair Clippers, of which the following is a specification.

The invention pertains to the class of hair clippers used by barbers and others for cutting the hair of persons, horses, dogs and other animals, and one object of the invention is to produce a novel construction of clipper in which the cutter-plate is afforded an ease of movement which tends to relieve it of frictional wear, while at all times being firmly seated over the comb-plate, and which facilitates the general use and operation of the instrument and lessens the strain on the hand of the barber or other person employing the same. A further purpose of the invention is to provide a construction which is durable and whose parts may be readily constructed and assembled and disassembled, and a further purpose of the invention is to retain in my novel construction many of the desirable features of known hair-clippers.

The invention will be fully understood from the detailed description hereinafter presented, reference being had to the accompanying drawings, in which:

Fig. 1 is a top view of a hair-clipper embodying my invention;

Fig. 2 is a vertical section, on a larger scale and partly broken away, through the same on the dotted line 2—2 of Fig. 1;

Fig. 3 is a bottom view, partly broken away, of the upper structure of the clipper above the comb and cutter plates;

Fig. 4 is a detached bottom view of a novel frame which I interpose between the cutter plate and the front lower surface of the cover-plate.

Fig. 5 is a transverse section of the same taken on the dotted line 5—5 of Fig. 4, and Fig. 6 is a vertical section through a portion of the clipper taken transversely through one end portion thereof and is presented to more fully illustrate the connection of the depending pins with the cover plate.

In the drawings, 10 designates the comb-plate, 11 the cutter-plate, 12 a cover-plate or covering frame, 13 one handle which is

rigid with said cover-plate and 14 the pivoted handle or lever by which the cutter-plate may be operated, as usual.

The cover-plate is domed upwardly and connected with the comb-plate by means of the usual threaded post 15 and studs 16. The post 15 is keyed at its lower end in the rearwardly extending portion of the comb-plate and at its upper portion passes through a hole in the cover-plate and is provided above the cover plate with a spring-washer 17 and thumb-nut 18, as usual. The studs 16 extend downwardly from the cover-plate and after passing through certain intermediate parts, hereinafter referred to, enter close-fitting holes in the comb-plate, as usual. The cutter-plate 11 has the usual parallel slots in its end portions through which the studs 16 pass, and these slots and studs perform the customary duties of aiding in securing the cutter plate and guiding the same in its sliding movements over the comb-plate, on which it is mounted.

The cutter-plate 11 in its rear edge has a recess 20 in which is confined a stud 21 extending downwardly from an inner portion of the operating lever 14, which lever is pivotally mounted, as usual, and is to be moved in one direction by hand and in the reverse direction or back to initial position by a coiled spring 22 in a well known manner. The movements of the lever 14 are communicated to the cutter-plate 11 and thereby said plate receives its usual sliding movements over the comb-plate.

In accordance with my invention the lower front face of the cover-plate 12 is smooth and flat and on this face I seat a special frame, numbered as a whole 23, which becomes interposed between said flat face and the top of the cutter-plate 11. The frame 23 comprises a top plate 24 which extends below the front of the cover plate or frame 12 and is formed with downwardly extending ends 25 and a downwardly extending front edge portion 26, from whose lower edge there extends rearwardly an auxiliary plate 27 which is upwardly depressed, as shown in the drawings and is less in width than the top-plate 24. The rear edge of the top-plate 24 has a concave recess 28 formed in it, and this recess is to permit of the arc movement of the stud 21 when the operating lever 14 is actuated to move

the cutter plate. The plate 24 is formed with apertures 29 adjacent to opposite ends of the recess 28, and these apertures permit the passage through them of the studs 16 which extend downwardly from the cover plate 12. The studs 16 and apertures 29 serve to maintain the frame 23 in predetermined position with respect to the cover plate 12 and at the same time permit said frame 23 to be applied to and removed from position at the lower flat surface of the front portion of the plate 12. The lower or auxiliary plate 27 of the frame 23 is formed in its end portions with slots 30 downwardly through which the lower portions of balls or ball-bearings 31 may project and be engaged by the upper front flat surface of the cutter-plate 11, as shown in Fig. 2. The auxiliary plate 27 of the frame 23 is above the forward flat surface of the cutter-plate 11, which surface I number 32, and the front depending edge 33 of the frame 23 created by the upper depression of the plate 27 laps downwardly to the front 25 of the surface 32 of the cutter-plate 11, as shown in Fig. 2, thereby serving to exclude hair or the like from lodging upon that portion of the cutter-plate inward beyond the cutting tongues thereof. The slots 30 are elongated, and preferably only two ball-bearings 31 will be located in each slot, and the long edges of the slots 30 are below the horizontal plane of the center of the ball-bearings 31, and this feature of construction is important in that thereby, with the upper depression of the plate 27, the ball-bearings 31 are prevented from escaping from the frame 23, and said frame 23 with the ball-bearings in position may be 35 handled as a unit and applied to or removed from the instrument without danger of said ball-bearings escaping from the slots 30 or from between the plates 24, 27.

The studs 16 extending downwardly from the cover plate or frame 12 thus extend through the apertures 29 of the frame 23 and through the usual slots in the cutter plate 11 and into the customary close-fitting holes in the comb-plate 10, and the 40 studs 16 when the parts are assembled and secured together by the post 15 and nut 18 serve to aid in properly connecting the comb-plate frame 23 and cover plate 12, and at the same time serve as guides for the 45 cutter-plate when moved by the lever handle 14 and spring 22. I minimize the frictional engagement of the cutter 11 with the comb-plate 10 by recessing the facing surfaces of both of said plates, as shown in Fig. 2, and the frictional engagement between the cutter-plate 11 and cover plate 12 is reduced to the minimum by the interpolation of the frame 23 containing and affording raceways for the ball-bearings 31, which are free to roll within the slots 30 and travel

with the cutter-plate 11 during the endwise back and forth or reciprocating movements of said plate.

My invention mainly resides in providing a construction embracing and arranged for the interposition of the box-like frame 23 between the lower front portion of the cover plate or frame 12 and top of the cutter plate 11, and in addition the frame 23 is of special form and construction adapting it to the instrument and to be applied thereto and removed therefrom without inconvenience. The studs 16 are well known in hair clippers, but in the present instance these studs are made long enough to extend through the apertures 29 of the frame 23 and also through the cutter plate 11 and comb-plate 10.

The frame 23 may be formed-up from a single piece of sheet metal or its members may be in several pieces secured together at adjacent edges, as may be preferred.

The operation of the hair-clipper will be understood without detailed explanation, since the cutter plate and comb-plate will be operated, as usual, through the handles 13, 14, spring 22 and the skill of the operator. In accordance with my invention however the cutter-plate 11 is relieved from unnecessary wear and friction by means of the ball-bearings 31 so that the cutter plate will have an ease of movement not heretofore present in hair-clippers and the strain on the hands of the operator will be lessened due to the lessening of the resistance of the cutter-plate to sliding movement.

What I claim as my invention and desire to secure by Letters-Patent, is:

1. In an instrument of the character described comprising a comb-plate, a cutter-plate thereon having a smooth uniform flat upper surface, a cover-plate having a smooth flat lower surface and means for operating the cutter-plate, in combination, a frame interposed between said flat upper surface of the cutter-plate and the said flat lower surface of the cover-plate and connected with the cover-plate, and ball-bearings carried by said frame and engaging the said upper flat surface of said cutter-plate, said frame comprising an upper plate member engaging the forward flat lower surface of said cover-plate to the front edge of said cover-plate, an exposed front member extending downwardly from the front edge of said upper plate member and at the front edge of said cover plate, ends and a rearwardly extending lower plate member containing slots in which said ball-bearings are located, said cover-plate having adjacent to its ends downwardly projecting studs which extend through said upper plate member, said cutter-plate and said comb-plate.

2. In an instrument of the character described comprising a comb-plate, a cutter-

- plate thereon having a smooth uniform flat upper surface, a cover-plate having a smooth flat lower surface and means for operating the cutter-plate, in combination, a frame interposed between said flat upper surface of the cutter-plate and the said flat lower surface of the cover-plate and connected with the cover plate, and ball-bearings carried by said frame and engaging the said upper flat 5 surface of said cutter-plate, said frame comprising an upper plate member engaging the forward flat lower surface of said cover-plate to the front edge of said cover plate, an exposed front member extending downwardly 10 from the front edge of said upper plate member and at the front edge of said cover plate, ends and a rearwardly extending lower plate member containing slots in which said ball-bearings are located, and said upper plate member being recessed out in its middle rear edge portion and at its end portions being extended rearwardly beyond said lower plate member and formed with vertical apertures, said cover-plate having adjacent to its ends downwardly projecting studs 15 which pass through said apertures in said upper plate member and through said cutter and comb plates.
3. In an instrument of the character described comprising a comb-plate, a cutter-plate thereon having a smooth uniform flat upper surface, a cover-plate having a smooth flat lower surface and means for operating the cutter-plate, in combination, a frame interposed between said flat upper surface of the cutter-plate and the said flat lower surface of the cover-plate and connected with the cover-plate, and ball-bearings carried by said frame and engaging the said upper flat 20 surface of said cutter-plate, said frame comprising an upper plate member engaging the forward flat lower surface of said cover-plate to the front edge of said cover plate, an exposed front member extending downwardly from the front edge of said upper plate member and at the front edge of said cover plate, ends and a rearwardly extending lower plate member containing slots in which said ball-bearings are located, and the lower edge portion of said front member and the front portion of said lower plate member being extended downwardly along the front of said frame below the rear portion of said lower plate member and below the flat surface of said cutter plate engaged by said balls.
4. In an instrument of the character described comprising a comb-plate, a cutter-plate thereon having a smooth uniform flat upper surface, a cover-plate having a smooth flat lower surface and means for operating the cutter-plate, in combination, a frame interposed between said flat upper surface of the cutter-plate and the said flat lower surface of the cover-plate and connected with the cover-plate, and ball-bearings carried by said frame and engaging the said upper flat 25 surface of said cutter-plate, said frame comprising an upper plate member engaging the forward flat lower surface of said cover-plate to the front edge of said cover plate, an exposed front member extending downwardly from the front edge of said upper plate member and at the front edge of said cover plate, ends and a rearwardly extending lower plate member containing slots in which said ball-bearings are located, and which lower plate member is, in rear of said front member, offset upwardly throughout its entire length to confine said ball-bearings in said slots and prevent their separation from said frame, said cover-plate having adjacent to its ends downwardly projecting studs 30 which extend through said upper plate member, said cutter plate and said comb-plate.
5. In an instrument of the character described comprising a comb-plate, a cutter-plate thereon having a smooth uniform flat upper surface, a cover-plate having a smooth flat lower surface and means for operating the cutter-plate, in combination, a frame interposed between said flat upper surface of the cutter-plate and the said flat lower surface of the cover-plate and connected with the cover-plate, and ball-bearings carried by said frame and engaging the said upper flat 35 surface of said cutter-plate, said frame comprising an upper plate member engaging the forward flat lower surface of said cover-plate to the front edge of said cover plate, an exposed front member extending downwardly from the front edge of said upper plate member and at the front edge of said cover plate, ends and a rearwardly extending lower plate member containing slots in which said ball-bearings are located, and the lower edge portion of said front member and the front portion of said lower plate member being extended downwardly along the front of said frame below the rear portion of said lower plate member and below the flat surface of said cutter plate engaged by said balls.

Signed at Newark in the county of Essex and State of New Jersey this 29th day of April, A. D. 1919.

WALTER HUNT REDMAN.
